Primary Examiner — Robert M Spear*Assistant Examiner* — Darcey E Heflin(74) *Attorney, Agent, or Firm* — Robert N. Lipszik(57) **CLAIM**

The ornamental design for a shoulder for a tire, as shown and described.

DESCRIPTION

FIG. 1 is a perspective view of a shoulder for a tire showing my new design, it being understood that the pattern repeats uniformly throughout the circumference of the tread;

FIG. 2 is a front elevational view thereof;

FIG. 3 is a right side elevational view thereof; the opposite side elevational view being identical thereto; and,

FIG. 4 is an enlarged fragmentary front elevational view thereof.

In the drawings, the broken lines adjacent shaded surfaces define boundaries of the claim; all other broken lines depict environmental subject matter and form no part of the claim.
